UNITED STATES PATENT OFFICE.

GEORGES MASSIP, OF LEVALLOIS, FRANCE.

OIL AND STEAM SEPARATOR.

1,181,470.

Specification of Letters Patent.

Patented May 2, 1916.

Application filed January 2, 1913. Serial No. 739,833.

To all whom it may concern:

Be it known that I, GEORGES MASSIP, a citizen of the French Republic, and resident of Lavallois, France, have invented certain new and useful Improvements in Oil and Steam Separators, of which the following is a specification.

It is the object of the present invention to construct an oil and steam separator in which the steam is treated in a peculiar manner by deflection by partitions so that the separating action of the partitions, is the same for all the sections of the fluid passage and that the entrance of the fluid is effected tangentially with respect to the partitions. If for instance the flow of a particular fluid is to be considered during its passage between two of the concentrically bent partitions, the transversal deflection to which each particle of said fluid is subjected will increase with the increase in the deflecting radius of the partitions. On the other hand it is necessary that the direction of flow of the fluid at its point of entrance is as nearly tangential to the partitions as possible, in order to avoid the particles entering between the partition walls in an opposite sense to that imparted to them by the centrifugal force.

In the accompanying drawing, Figures 1 and 2 illustrate a preferred form of separator in longitudinal and cross section.

The curved partitions 1 are parallelly and vertically disposed within a casing 3 between the inlet and outlet openings 9 and 6 thereof.

Copies of this patent may be obtained for five cents each, by addressing the "Commissioner of Patents, Washington, D. C."

The partitions are provided with grooves or channels 4 into the bottom parts of which the drops of liquid carried along are guided, whereafter they are discharged in the lower 40 part of the apparatus at 5, and leave through the opening 6'.

The partitions 1 are formed so as to present themselves at the entrance of the fluid exactly tangentially as shown at 7 and 8, 45 parallel to the axis of the apparatus in such a manner that the particles enter the nests or bunches and roll along said walls parallel to the same.

I claim:

An apparatus of the character described comprising a casing having inlet and outlet openings in opposite sides thereof for the fluid in combination with a series of parallel vertically disposed curved partitions arranged within the casing between the inlet and outlet openings, the partitions being so placed relatively to the inlet opening that the tangents of the curved partitions at the vertical edges thereof adjacent the inlet 50 opening are parallel to the axis of the inlet opening, thus permitting free entrance of the steam admitted through the inlet opening to the space between the curved partitions. 60

In testimony whereof I affix my signature in presence of two witnesses.

GEORGES MASSIP.
